(57) **CLAIM**

An electronic alarm clock, as shown and described.

DESCRIPTION

FIG. 1 is a front view of an embodiment of an electronic alarm clock;

FIG. 2 is a back view of the electronic alarm clock shown in FIG. 1;

FIG. 3 is a left side view of the electronic alarm clock shown in FIG. 1;

FIG. 4 is a right side view of the electronic alarm clock shown in FIG. 1;

FIG. 5 is a top view of the electronic alarm clock shown in FIG. 1;

FIG. 6 is a bottom view of the electronic alarm clock shown in FIG. 1;

FIG. 7 is a left perspective view of an embodiment of an electronic alarm clock; and,

FIG. 8 is a right perspective view of an embodiment of an electronic alarm clock.

The broken line showing of portions of the electronic alarm clock is for the purpose of illustrating unclaimed portions of the electronic alarm clock and forms no part of the claimed design.

1 Claim, 4 Drawing Sheets
